PRECISION LONG REACH HOLE PUNCH

This invention relates to a precision long reach hole punch. More particularly, this invention relates to a long reach hole punch wherein a perforating tool can be precisely located with respect to a workpiece by visual sighting.

A need has arisen in the data processing field for a manually operated punch capable of making a precisely placed perforation on sheet material such as paper, cardboard, sheet plastic or the like. For example, in the so-called "punch correlation" data storage and retrieval system, a data sheet is provided with indicia, such as letters or numbers, arranged in vertical columns and horizontal rows. Perforation of one indicium at a given column and row signifies a "bit" of information. The information-bearing indicia are usually closely spaced, for reasons of economy. In one well-known form used in punch correlation, adjacent indicia in a given column are spaced by only about one-eighth inches, and indicia in adjacent columns are spaced by about three-sixteenth inches. The need for accurate placement of the perforations is therefore apparent.

It is a principal object of this invention to provide apparatus for making a precisely positioned perforation in sheet material. Such an object is accomplished, in a presently preferred form of the invention, by apparatus including a fixed base capable of resting on a desk or table top, and a moveable punch associated with a base. The base is provided with die opening into which the punch may be telescopically received. Means bias the punch to the inoperative position, however, spaced from the die opening. The punch, in the preferred form, includes a centrally disposed bore, so that an operator may sight directly through the punch, to see the indicium at which the perforation is to be made.

I am aware of devices such as the one shown in U.S. Pat. No. 2,394,377, wherein a hollow punch is used. The device shown in that invention uses the hollow punch only as a receptacle for punched out portions, and hence, does not and cannot function in a manner similar to my apparatus, to permit visual sighting for precision placement of the punch.

Another object of this invention is to provide a long reach punch, capable of placing a perforation at any desired point on a sheet of material. For this purpose, the apparatus in accordance with this invention includes a punch arm pivoted at one of its ends and having a punch at the other, the punch being so spaced from the pivot as to provide a reach capable of placing a punched opening at any point on an 8 1/2" x 11" inch workpiece. Such an arrangement, it has been found, permits optimum utilization of the above-mentioned sighting feature, and results in a far more useful device than conventional hole punches.

Other objects will appear hereinafter.

For the purpose of illustrating the invention, there is shown in the drawings a form which is presently preferred; it being understood, however, that this invention is not limited to the precise arrangements and instrumentalities shown.

FIG. 1 is a perspective view of an apparatus in accordance with the invention.

FIG. 2 is a partial side elevational view of the apparatus in FIG. 1.

FIG. 3 is a cross-sectional view taken along the line 3-3 in FIG. 1.

FIG. 4 is a cross-sectional view, similar to FIG. 3, but showing the apparatus in another operative position.

FIG. 5 is a top plan view, partly broken away taken along the line 5-5 in FIG. 3.

FIG. 6 is a cross-sectional view taken along the line 6-6 in FIG. 2.

FIG. 7 is a cross-sectional view taken along the line 7-7 in FIG. 3.

FIG. 8 is a cross-sectional view taken along the line 8-8 in FIG. 3.

Referring now to the drawings in detail, there is seen in FIG. 1 hole punch apparatus designated generally by the reference numeral 10.

The apparatus 10 includes a base, designated generally by the reference numeral 12, and a punch arm, designated

generally by the reference numeral 14, movably coupled to the base 12 in a manner to be described in detail later.

Referring to FIGS. 3, 4, 7 and 8, the base 12, in the illustrated form of the invention, includes a panlike inner case 16, 5 provided with spaced footpads 18 and 20 for contacting a supporting surface.

Associated with the inner case 16 is an outer case 22. The outer case 22 is provided with a depending radius portion 24, complimentary with a radius portion 26 on the inner case 16. 10 The dimensions of the inner case 16, it should be understood, are such that the inner case 16 can be received in nested relation within the outer case 22.

The depending radius portion 24 and the portion 26 of the inner case interconnect the inner and outer cases 16, 22, at 15 one end. The other end of the inner and outer cases 16 and 22 are held in interengagement by the snap action of complimentary inwardly directed "dimples" 28, 30, 32 and 34 on the inner and outer cases 16, 22.

Referring to FIGS. 2, 3, 4 and 5, the inner case 16 is 20 preferably provided with a tab 36 at one of its ends, such tab providing the means for applying leverage to the inner case 16 to break the snap-action interlock provided by the dimples 28-34. As is depicted by the dotted line portions in FIG. 4, the application of force to the tab 36 can cause rotation of the inner case 16 with respect to the outer case 22 about a pivot provided by the depending radius portion 24 of the outer case 22 and the complimentary portion 26 of the inner case 16.

Referring to FIGS. 6 and 7, a pair of spaced, generally parallel ears 38 and 40 extend upwardly from the outer case 22. The ears 38 and 40 provide an anchorage point for the punch arm 14.

The punch arm 14, in the presently preferred form of the invention, includes an outer case 42 and an inner case 44 35 nestably received in the outer case 42. Both the outer case 42 and the inner case 44 are pivotably coupled to each other and to the ears 38 and 40 by a pivot pin 46. Thus, as is seen in FIGS. 6 and 7, the ears 38 and 40 are received between the outer and inner cases 42, 44 and the pivot pin 46 passes successively through the outer case 42, the ear 38, the inner case 44, the ear 40 and the opposite side of the outer case 42. Washers 48 may be provided between the ears 38 and 40 and the outer and inner cases 42, 44 to facilitate rotation about the pivot pin 46.

Referring to FIGS. 2 through 5, a flat spring 50 is provided in engagement with the underside of the inner case 44 of the punch arm 14. The spring 50, it should be understood, exerts an upward force on the underside of the inner case 44, to bias the punch arm 14 in a counterclockwise direction as viewed in 50 FIGS. 1 through 4. Stops 52 and 54, perhaps best seen in FIG. 8, limit such movement of the punch arm 14 under the influence of the spring 50.

A compression spring 56 is received between the outer and inner cases 42 and 44, and tends to bias the cases apart, away 55 from a nested relation. A guide pin 58 coupled to one of the cases 42, 44, and associated with a slot, such as the illustrated slot 60, in the other of the cases serves to limit relative movement of the outer and inner cases 42, 44.

A punch 62 is affixed to the outer case 42 of the punch arm 14, and extends downwardly through an opening 64 in the inner case 44.

The outer case 22 of the base 12 is provided with a die opening 68, juxtaposed to the lower end of the punch 62.

The mode of operation of the apparatus 10 in perforating material is believed apparent.

Referring to FIGS. 3 and 4, a workpiece to be perforated, such as the illustrated sheet 70, may be positioned between the punch arm 14 and base 12 in juxtaposition to the punch 62 and die opening 68. The application of a downward force on the end of the punch arm 14 remote from the pivot pin 46 results in an initial rotation of the entire punch arm 14 about the pivot pin 46, against the bias of the spring 50. Initially, a lower portion of the inner case 44 of the punch arm 14 contacts the workpiece 70, and in effect, clamps the workpiece 70

securely to an upper surface of the outer case 22 of the base 12. Continued downward force on the punch arm 14 results in rotation of the outer case 42 with respect to the inner case 44, against the bias of the compression spring 56. Such rotation causes the punch 62 to pass through the workpiece 70 and into the die opening 68. The punched out portion of the workpiece 70, designated by the numeral 72, remains in the hollow chamber formed by the inner and outer cases 16 and 22 form the base 12.

Release of pressure on the punch arm 14 causes the various elements to revert to their positions shown in FIG. 3.

The portion of the punch arm 14 upon which force is applied to initiate a punching operation may be referred to for convenience as a handle portion. Such handle portion may be provided, if desired, with a transparent handle element 74.

An important aspect of the present invention is illustrated in FIG. 5. Referring to such figure, and also to FIGS. 3 and 4, it can be seen that the punch 62 is a hollow member, which includes a central bore 76. The punch 62 is coupled to the outer case 42 by a peripheral flange, weld or other means, such that the lower end of the bore 76 may be viewed from above.

Referring to FIG. 5, it is apparent that a particular indicium 80 on the workpiece 70 is visible through the bore 76 of the punch 62. It is evident, therefore, that the punch 62 can be precisely located by visual sighting, so that operation of the apparatus 10 removes only a particular desired part of a workpiece. The transparent handle element 74 does not interfere with viewing through the bore 76, and serves to prevent the accumulation of foreign matter in such bore 76.

It is particularly desirable that the apparatus 10 in accordance with the present invention provide a long reach, so as to permit punching at any point on a given workpiece. For example, it has been found that a spacing of approximately 7½ inches from the centerline of the punch 62 to the ears 38 and 40 provides an apparatus capable of punching at any point on an 8½ by 11 inch workpiece.

The present apparatus 10 provides a simple and effective hole punch apparatus, capable of precise placement by optical sighting, in a manner not heretofore known in the art.

The present invention may be embodied in other specific forms without departing from the spirit or essential attributes thereof and, accordingly, reference should be made to the appended claims, rather than to the foregoing specification as indicating the scope of the invention.

I claim:

1. Apparatus for perforating sheet material comprising an elongated base, said base having a die opening at one end thereof, an elongated punch arm, said punch arm being comprised of an elongated inner casing and an elongated outer casing, said outer casing being open along one side and said inner casing being nestingly received through said open side, one end of said inner casing being pivotally coupled to said outer casing for movement relative thereto, means for urging 10 said outer casing and said inner casing apart, said inner casing and said outer casing being pivotally coupled to said base for movement relative thereto, means for urging said outer and inner casing away from said base, said inner casing having a vertically disposed opening at one end, a punch mounted on 15 said outer casing and depending downwardly therefrom in alignment with said vertically disposed opening in said inner casing, said punch being an elongated member having an axial bore, said outer casing having an opening overlying said punch so that said axial bore is visible, a transparent handle member 20 mounted on said outer casing in overlying relation to said axial bore, and said punch and said die are axially aligned so that indicia on the material to be punched may be precisely positioned by sighting through said transparent handle and said bore.
2. An apparatus as defined in claim 1 wherein said inner and outer casings are coupled to a common pivot for rotation with respect to each other and to said face.
3. Apparatus in accordance with claim 1, wherein said base comprises a pair of nested inner and outer members, said die opening being disposed in an upper surface of one of said members, the other of said members having means thereon for contacting a support surface, and snap-action means 25 removably interconnecting said members.
